UNITED STATES PATENT OFFICE.

EDWARD WILLIAM HEDBERG, OF CHICAGO, ILLINOIS.

SWITCH-CONTROLLING MECHANISM.

1,258,679.

Specification of Letters Patent. Patented Mar. 12, 1918.

Application filed June 29, 1916. Serial No. 106,569.

To all whom it may concern:

Be it known that I, EDWARD W. HEDBERG, a citizen of the United States, residing at Chicago, in the county of Cook and State 5 of Illinois, have invented certain new and useful Improvements in Switch-Controlling Mechanisms, of which the following is a specification.

This invention relates to automatic limit 10 switches or the like. I have herein shown my invention applied to a hot water heating system, but it will be apparent from the following description and drawings that the invention may be otherwise applied with 15 but slight modifications.

One object of my invention is to provide improved limit switch means which is operable automatically and wherein the limits are adjustable.

20 With the foregoing and other objects in view, the invention consists of the novel combination and arrangement of parts illustrated in the accompanying drawings hereinafter more specifically described and particularly pointed out in the claims.

25 In the drawings I have shown in Figure 1 a diagrammatic elevational view of a hot water system to which my invention has been applied. Fig. 2 is an enlarged front elevation of the limit switch shown in Fig. 30 1. Fig. 3 is an enlarged cross section taken on line 3—3 of Fig. 2 of the limit switch shown there and the operating mechanism therefor shown in Fig. 1. Fig. 4 is a rear elevational view along the line 4—4 of Fig. 35 3. Figs. 5, 6, 7 and 8 are enlarged sectional views of the limit switch taken on lines 5—5, 6—6, 7—7 and 8—8 of Fig. 2. Fig. 9 is a sectional view taken on line 9—9 of 40 Fig. 3.

45 In Fig. 1 is shown a diagrammatic view of a hot water heating system comprising a boiler 1 with a check 2 and a draft 3. The usual expansion chamber 4 is connected to the boiler by any convenient means as the pipe 5. To the chamber 4 is attached an auxiliary chamber 6 containing the operating mechanism for the limit switch 7. The operating mechanism may, however, if 50 preferred be installed directly in the expansion tank. The switch 7 is connected by suitable wires 8 to the motor means indicated at 9. The chains 10 are connected to the check 2 and the draft 3 and are operable by the motor means in a manner to be 55 hereinafter more specifically described.

The limit switch 7 for controlling the motor circuit comprises a U-shaped block of insulating material with two side members 11 and 12 spaced apart and connected at the 60 top by a cross-bar 13. The block is supported by the brackets 14 which are attached to the auxiliary tank 6. Each of said members 11 and 12 is slotted at 15 and 16, respectively, and is adapted to receive stop 65 members comprising a contact stud 17 carrying a plate 18^a or 18^b and a nut 19, said stop members being adjustable in said slots. Each of said members 11 and 12 carries a conductor strap 20 slotted similarly to the 70 members so that said slots register with the slots in the members when the switch is assembled. Herein I have shown the conductor strap sunk flush with the insulated member and extending but a portion of the 75 length of that member.

The space between the members 11 and 12 is provided with two conductor guides 21 which are electrically connected to a third conductor strap 22 which is best shown 80 in Figs. 3 and 4. A bar 23 near its upper end freely passes through the cross-bar 13 and at its lower end carries a contact plate 24 and a spring clip 25 provided with shoes 26. This spring clip 25 is adapted to slide 85 up and down the block upon the surface of the members opposite to which the conductor straps are attached and in so doing encounters the contact plates 18^a and 18^b which have been placed at the desired 90 points. The shoe does not contact the plates while intermediate these positions and the motor circuit will remain open.

At the lower end of the U-shaped block are located the terminals 27 of the switch 7. 95 These comprise the usual contact pins and knurled nuts for connecting the wires 8^a, 8^b and 8^c to the straps 20 and 22. To the upper end of the switch the operating mechanism is attached in the following manner. 100 The bar 23 is rigidly connected to a cross-bar 28 which in turn is similarly connected to a rod 29. The rod 29 extends downwardly and freely through the cover of the auxiliary tank 6 and is connected to a movable float member 30 which follows the water level in the expansion chamber 4, the auxiliary tank being connected to and communicating with the expansion chamber in any suitable manner. The float member 105 30 may, however, be installed in the expansion chamber if desired without departing from

the scope of the invention. It is seen that as the float 30 rises and falls, following the rise and fall of the water level in the expansion tank, the slideable contact clip 25 will 5 rise and fall with it and will close the switch when the water has reached the highest desirable level or when it has reached the lowest desirable level. In this manner the motor will be actuated to check the fire or to 10 increase the fire respectively and this switch will remain closed as long as either condition above mentioned exists.

The complete cycle of operation of the various parts is as follows: Assume that a 15 high fire has raised the temperature of the water and the level of the water in the expansion tank has been raised correspondingly. This raises the float which in turn raises the slideable switch element until the 20 upper limit of travel is reached as indicated by the position of the upper switch contact 18^b. As long as the level of the water remains or exceeds the level at which the float has closed this switch, the switch will continue to remain closed. Closing this switch 25 completes the motor circuit which will remain closed until the motor has rotated sufficiently whereupon the branch of the motor circuit through plate 18^b will be opened at the motor by suitable means not shown and the other branch through plate 18^a will be closed at the motor and will remain so until the clip 26 contacts plate 18^a and the motor is again actuated. 30 It is obvious that various changes may be made in the embodiment herein illustrated without departing from the spirit and scope of the invention, and while I have described in some detail a specific embodiment of my 35 invention which I deem to be new and advantageous, I do not desire to be understood as limiting myself in respect to the broader 40

features of my invention except as stated in the appended claims.

I claim as my invention:

1. A limit switch having, in combination, a U-shaped insulating body comprising two side members spaced apart and having two parallel slots, limit stops adjustable in the slots of said members, operating terminals adapted to be connected to said stops, a movable member connected to an additional terminal and adapted to slide in the space between said side members and to be in contact with but one of said stops at the same instant for closing a circuit through the switch, and means for sliding said movable member.

2. A limit switch having, in combination an insulating body portion having conducting straps thereon, limit stops connected to two of said straps, a conducting guide connected to a third strap and a movable contact member slideable on said guide and having a pair of arms each adapted to contact one of said stops for closing different circuits through the limit switch.

3. A limit switch including an insulating body having two spaced parallel slots, a conducting stop adjustable in each slot, a conducting strap for each of said stops adjacent said slots, a conducting guide located between said slots, an operating terminal connected to each of said conducting straps and said guide, a conducting member slideable in said guide and having a contacting arm for each stop, and means for moving said member, each stop being arranged to be engaged by its arm in the movement of the member to complete a circuit with its conducting strap and the guide.

In testimony whereof I have hereunto set my hand.

EDWARD WILLIAM HEDBERG.
